UNITED STATES PATENT OFFICE

2,061,333

SINTERING MACHINE

Chester Skinner, Donora, Pa., assignor to The
American Steel and Wire Company of New
Jersey, a corporation of New Jersey

Application March 26, 1935, Serial No. 13,161

6 Claims. (Cl. 259—17)

This invention relates to sintering machines of the type which includes a sintering bed and a spout or hopper which depends over this bed so as to distribute the material to be sintered thereon, one of the objects being to improve this type respecting its ability to properly handle finely divided materials, such as flue dust, zinc oxide, fine flotation products, etc. Other objects may be inferred.

10 An example of the invention is illustrated by the accompanying drawing, in which Figure 1 is a cross-section of a sintering machine embodying the principles of the invention, Figure 2 is a longitudinal section taken from the line II—II in Figure 1, and Figure 3 is a cross-section taken from the line III—III in Figure 2.

Referring to this drawing, a sintering machine is illustrated as including a movable sintering bed consisting of a series of pallets 1 which ride 20 on tracks 2, an open-bottomed hopper 3 arranged over this bed, a transversely swinging spout 4 depending into the hopper 3 over the bed for distributing the material to be sintered thereon, and a bar 5 fixed to the spout 4 for a limited swinging movement relative thereto and depending therefrom with its lower end portion 5^a shaped so as to be in the path of material discharged from the spout 4, and terminating adjacent the bed.

30 Figure 3 shows a convenient means for so fixing the bar 5 to the spout 4. This means consists of a clip 6 which is welded to the spout 4 and is shaped as at 6^a to provide a slot through which the bar 5 may be passed, a bolt 7 being passed through a hole in the bar 5 so as to retain the latter.

The bar 5 is illustrated as having its lower end portion so curved as to bring its extreme end into proximity with the end of the hopper 3. No danger will result from the bar 5 striking the sides of the hopper, because of its ability to swing slightly relative to the swinging spout 4.

The swinging spout 4 is illustrated as being connected by a rod 8 to a bell-crank 9 which is 45 in turn connected to a rod 10, it being understood that the latter may be reciprocated by any convenient means.

In operation, the material to be sintered is fed to the spout 4 while the latter is swinging and 50 the pallets 1 are moving. As the material discharges from the spout 4 it drops and strikes the end portion 5^a of the bar 5. This tends to break its fall and at the same time cause disintegration of any lumps which might have been formed 55 during its feeding to or through the spout 4. Since the material leaves the spout 4 in the form of a stream, it tends to form a pile which travels across the bed provided by the pallets 1. The end portion 5^a terminates sufficiently closely to 60 this bed to bring at least its extreme end into

the peak of the piles of the material which has formed on the latter when discharged thereon from the spout 4. It follows that the swinging action of the spout 4 also swings the bar 5 so that its extreme end constantly agitates the peak 5 of the material. This has been found to be an important factor in the prevention of the formation of lumps and in that it provides an assurance that the material will be evenly distributed over the sintering bed.

10 I claim:

1. A sintering machine including the combination of a sintering bed, a depending spout over said bed for distributing the material to be sintered thereon, and a bar depending from said spout and having its lower end portion shaped so as to be in the path of material discharged from said spout.

2. A sintering machine including the combination of a movable sintering bed, a transversely swinging depending spout over said bed for distributing the material to be sintered thereon, and a bar depending from said spout with its lower end adjacent said bed.

3. A sintering machine including the combination of a movable sintering bed, a transversely swinging depending spout over said bed for distributing the material to be sintered thereon, and a bar depending from said spout with its lower end portion shaped so as to be in the path of material discharged from said spout and terminating adjacent said bed.

4. A sintering machine including the combination of a movable sintering bed, an open-bottomed hopper arranged over said bed, a transversely swinging spout depending into said hopper over said bed for distributing the material to be sintered thereon, and a bar fixed to said spout for limited swinging movement relative thereto and depending therefrom with its lower end adjacent said bed.

5. A sintering machine including the combination of a movable sintering bed, an open-bottomed hopper arranged over said bed, a transversely swinging spout depending into said hopper over said bed for distributing the material to be sintered thereon, and a bar fixed to said spout for limited swinging movement relative thereto and depending therefrom with its lower end portion shaped so as to be in the path of material discharged from said spout and terminating adjacent said bed.

6. A sintering machine including the combination of a sintering bed, a spout depending over said bed so as to distribute the material to be sintered thereon and means for agitating the peak of the material as formed on said bed when discharged thereon from said spout.

CHESTER SKINNER. 60
